UNITED STATES PATENT OFFICE.

ANDREAS RADOVANOVIC, OF ZURICH, SWITZERLAND.

PUMP.

SPECIFICATION forming part of Letters Patent No. 784,178, dated March 7, 1905.

Application filed November 2, 1904. Serial No. 231,139.

To all whom it may concern:

Be it known that I, ANDREAS RADOVANOVIC, a subject of the Emperor of Austria-Hungary, residing at Zurich, Switzerland, have invented 5 certain new and useful Improvements in Pumps, of which the following is a specification.

This invention relates to pumps with means for closing the suction-valve by hydraulic 10 pressure, and according thereto a pump is provided with a plunger-cylinder communicating with the pressure-chamber and being closed against the pump-chamber by a plunger-piston forming an extension of the pump- 15 piston. By means of radial channels, which are only uncovered at the position of the pump-piston corresponding with the end of the suction-stroke, the plunger-cylinder communicates with a cylinder the piston of which 20 is formed by a projection of the suction-valve, so that the closing of this valve is effected at the end of the suction-stroke.

In the accompanying drawings, which illustrate examples of apparatus according to this 25 invention, Figure 1 is a vertical longitudinal section of such a pump. Fig. 2 is a detail view showing a modified structure of one part of the pump; and Fig. 3 is vertical longitudinal section of a modified constructional 30 form of a pump according to the invention, the delivery-valve not being shown.

The pump-chamber m , as shown in Fig. 1, is provided on its top with a delivery-valve and on the bottom with a suction-valve. The 35 pump-piston p is provided with an extension forming the plunger-piston p' . The latter fits into a cylinder r , which communicates by the conduit l with the pressure-chamber situated above the delivery-valve and by radial 40 channels or holes p'' with the cylinder a . The holes p'' are disposed in the cylinder r in such a manner relatively to the plunger-piston p' that these holes communicate with the side of the plunger-cylinder communicating with the 45 pressure-conduit only at the outermost or extreme position of the plunger-piston, (shown in the drawings,) which position corresponds with the end of the suction-stroke of the pump-piston. In the cylinder a may move 50 the piston k , forming a rigid projection of the

suction-valve. This arrangement operates as follows: At the end of the suction-stroke the radial holes p'' are uncovered by the plunger-piston p' , whereby the fluid under pressure gains entrance from the conduit l and from 55 the cylinder r into the cylinder a , where it acts on the piston k , and thereby causes the suction-valve to close.

In the modified constructional form shown in Fig. 2 the cylinder a is provided with radial holes o , which are disposed relatively to the piston k of the suction-valve in such a manner that they are uncovered at the closed position of the suction-valve. This arrangement operates as follows: The pressure fluid 60 flows first from the pressure-conduit into the cylinder a and causes the closing of the suction-valve, as described; but prior to the moment of the complete closing of the suction-valve the piston k uncovers the holes o of the 65 cylinder a . Now the pressure fluid is able to flow into the pump-chamber m , so that the pump-piston at the beginning of the pressure-stroke meets the full pressure in the chamber m . 70

Fig. 3 shows a constructional form of the pump wherein the suction-valve is disposed coaxial with the pump-piston p . In this case the piston k has an annular shape and may transmit the fluid-pressure to the suction-valve 75 by means of an elastic buffer b . After the closing of the suction-valve (this position is shown in Fig. 3) the buffer b , situated between the piston k and the suction-valve, is further compressed by the fluid-pressure. The piston k moves still farther to the right and uncovers an annular opening r' , through 80 which the pressure fluid flows into the pump-chamber. 85

In case where an elastic connection is provided between the piston k (shown in Fig. 2) and the suction-valve the arrangement may be such that at the moment of the closing of the suction-valve the piston k is still covering the holes o and uncovers the latter only when 90 the elastic buffer, situated between the piston and the suction-valve, is compressed by the hydraulic pressure in the cylinder a . By suitably selecting the cross sections or areas of the holes p'' and o and by causing the uncov- 95

ering of these holes in due time it can be at-
tained that the suction-valve is closed just at
the moment of the reversing of the stroke, so
that the full pump-pressure is obtained in the
5 chamber m , and any hammering is prevented
when the pump is running.

By the described arrangement of the pres-
sure-fluid supply the effect is produced that
the pressure fluid continuously presses on the
10 working area of the piston p' , so that the
pump-rods even at the suction period are
strained, but only in one direction, and therefore
do not suffer by reverse of pressure.

The relative position of the suction-valve,
15 or eventually of a number of suction-valves,
and of the axis of the pump-plunger can be
arranged as desired.

The described closing of the suction-valve
by hydraulic pressure can be employed with
20 pumps and valves of all kind.

I claim—

1. In a hydraulic pump, the combination
with a forcing-piston, pressure and pump
chambers and suction and delivery valves, of
25 means controlled by the piston to admit water
under pressure to the suction-valve, the pres-
sure of said water being greater than the pres-
sure of the water in the suction-chamber and
means controlled by the movement of the suc-
30 tion-valve to vent said water under pressure
into the pump-chamber, substantially as de-
scribed.

2. In a hydraulic pump, the combination
with a forcing-piston, pressure and pump
35 chambers, and suction and delivery valves, of
a connection between the suction-valve and
pressure-chamber, and a valve on the end of
the piston to admit water from the pressure-
chamber to the suction-valve to close the same,
40 substantially as described.

3. In a hydraulic pump, the combination
with a forcing-piston, pressure and pump
chambers, and suction and delivery valves, of
45 means to admit water from the pressure-cham-
ber to the suction-valve and means controlled
by the movement of said valve to vent said
water into the pump-chamber, substantially
as described.

4. In a pump, the combination with a forc-
50 ing-piston, pressure and pump chambers, and
suction and delivery valves, of means con-
trolled by the piston to admit water from the
pressure-chamber to the suction-valve to close
the same and means controlled by the move-
55 ment of said valve to vent said water into the
pump-chamber, substantially as described.

5. In a pump, the combination with a forc-
ing-piston, pressure and pump chambers, and
suction and delivery valves, of a cylinder con-
60 nected to the pressure-chamber, and a piston

coöperating therewith, said piston connected
to the suction-valve and a valve on the end of
the forcing-piston to admit water under a pres-
sure greater than the pressure in the pump-
chamber, to said piston to close the suction-
valve, substantially as described. 65

6. In a pump, the combination with a forc-
ing-piston, pressure and pump chambers, and
suction and delivery valves, of a cylinder hav-
ing outlet-ports and a piston coöperating with
70 the cylinder, said piston connected to the suc-
tion-valve and a valve controlled by the forc-
ing-piston to admit water under pressure into
the pump-chamber to said piston, to close the
suction-valve and open the ports in the cylin-
75 der to vent the water under pressure into the
pump-chamber, substantially as described.

7. In a pump, the combination with a forc-
ing-piston, pressure and pump chambers, and
suction and delivery valves, of a ported valve-
80 casing, a pipe connecting the casing with the
pressure-chamber, a piston-valve in said cas-
ing and forming an extension of the forcing-
piston, a cylinder and a piston coöperating
85 therewith, said cylinder connected to the valve-
casing, whereby water from the pressure-
chamber will be admitted to the piston to close
the suction-valve, substantially as described.

8. In a pump, the combination with a forc-
ing-piston, pressure and pump chambers, and
suction and delivery valves, of a ported cy-
lindrical valve-casing, a pipe connecting one
90 end of the casing with the pressure-chamber, a
piston-valve in said casing forming an exten-
sion of the forcing-piston, a cylinder and a pis-
ton coöperating therewith, said cylinder con-
95 nected to the valve-casing and means con-
trolled by the piston to vent water from the
pressure-chamber into the pump-chamber,
substantially as described. 100

9. In a pump, the combination with a forc-
ing-piston, pressure and pump chambers, and
suction and delivery valves, of a ported cy-
lindrical valve-casing, a pipe connecting the
105 casing and pressure chambers, a cylinder form-
ing an extension of the valve-casing, a piston
external of said cylinder and connected to the
suction-valve, and a piston-valve forming an
extension of the forcing-piston to admit wa-
110 ter from the pressure-chamber to the piston
connected to the suction-valve and move said
piston to vent the water into the pump-cham-
ber, substantially as described.

In testimony whereof I have hereunto set
my hand in presence of two subscribing wit-
nesses. 115
